UNITED STATES PATENT OFFICE

2,437,758

DARNING LAST

Jay L. Saulsberry, Tucumcari, N. Mex.

Application May 24, 1946, Serial No. 672,034

2 Claims. (Cl. 223—100)

1

This invention relates to new and useful improvements and structural refinements in darning lasts, and the principal object of the invention is to provide a device of the character herein described, such as may be conveniently and effectively employed for the darning, or mending of hose.

A further object of the invention is to provide a darning last which may be readily applied to or removed from the hose and in which the hose, when applied, is held in such position, that the portion or area thereof which is being mended, is freely and conveniently accessible.

Another object of the invention is to provide a darning last which is simple in construction and which can not easily become damaged.

An additional object of the invention is to provide a darning last which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a top plan view of the invention,

Figure 2 is a side elevation thereof,

Figure 3 is an end view of the same,

Figure 4 is a cross sectional view, taken in the plane of the line 4—4 in Figure 1,

Figure 5 is a side elevation, similar to that shown in Figure 2, but illustrating the base plate and the clamping piece of the invention in the separated position,

Figure 6 is a fragmentary perspective view of the base plate, and

Figure 7 is a fragmentary perspective view of the clamping piece.

Like characters are used to designate like parts in the specification and throughout the several views.

Referring now to the accompanying drawing in detail, the invention embodies in its construction a base plate designated generally by the reference character 10, the same consisting of a sheet of suitable material 11, having an elongated configuration and being provided substantially at the center thereof with an opening 12.

The end portions of the sheet 11 are arcuated to provide a pair of detents 13, the purpose of which will be hereinafter more fully explained.

A suitable strip of material is formed to constitute a frame 14, this being secured to the sheet 11 and surrounding the aforementioned opening 12.

2

The clamping piece designated generally by the reference character 15 consists of a further strip of material 16, this being configurated complementarily to the strip or frame 14 and being adapted for removable insertion into the same.

A pair of resilient clips 17 are hingedly connected as at 18 to the relatively opposite ends of the strip 16, the free ends of the clips 17 being formed with the arcuated portions 19.

10 When the invention is placed in use, the hose is positioned (single thickness) between the separated base plate 10 and the clamping piece 15, the portion or area of the hose which is to be mended being disposed over the opening 12.

15 Thereupon, the clamping piece 15 is positioned on the base plate 10, so that the strip 16 is received in the frame 14. It will be apparent that in this manner, the desired portion of the hose may be stretched over the opening 12.

20 To prevent the remaining portion of the hose from interfering with the mending operation, said remaining portion is clamped between the detents 13 and the arcuate portions 19. The undesired portion of the hose will thus be retracted, 25 or held away from the portion which is being mended.

The action of the clip 17 is best illustrated in the accompanying Figure 5, the same being shown therein by the full lines and by the phantom lines 20.

30 It is believed that the advantages and use of the invention will be clearly understood from the foregoing disclosure and accordingly, further description thereof at this point is considered unnecessary.

35 While in the foregoing there has been shown and described the preferred embodiment of this invention, it is to be understood that minor changes in the details of construction, combination and arrangement of the parts may be resorted to without departing from the spirit and scope of the invention as claimed.

40 What I claim as my invention is:

45 1. A darning last comprising in combination, an elongated base formed with an opening substantially at the center thereof, a frame secured to said base and surrounding said opening, a clamping piece removably receivable in said frame, and a pair of spring clips hingedly connected to said clamping piece, said clips being releasably engageable with the ends of said base.

50 2. A darning last comprising in combination, an elongated base plate formed with an opening substantially at the center thereof, and having its end portions arcuated to provide a pair of

detents, a frame secured to said base and surrounding said opening, a clamping piece comprising an endless strip of material adapted for removable insertion into said frame, and a pair of resilient clips hingedly connected at one end thereof to the relatively opposite ends of said clamping piece, the remaining ends of said clips being arcuated and releasably engaging said detents.
